CUTTING TORCH

Clifford C. Anthes, Union, N.J., assignor to Union Carbide Corporation, a corporation of New York
Filed Oct. 19, 1960, Ser. No. 63,585
1 Claim. (Cl. 158—27.4)

This invention relates to cutting torches, and more particularly to oxyfuel blowpipes employed for severing ferrous metals and the like.

The use of fuel gases other than acetylene for hand and machine metal-cutting operations has been increasing steadily over the past few years. Indications are that this increase will continue due in large part, to the considerable cost advantage enjoyed by such gases as methane or natural gas. Such fuel gases, supplied from low pressure (½ p.s.i. or less) gas lines in particular, have become increasingly popular as a source of fuel for gas cutting operations.

This shift to low pressure fuel gases for gas cutting has necessitated the development of cutting torch apparatus particularly tailored for use with these fuels. For example, torches with greater preheat gas flow capacity than could be supplied by standard oxy-acetylene cutting torches are required. This is due to the fact that greater volumes of both fuel gas and preheat oxygen are required to provide the equivalent heat output or preheat flame effectiveness produced using acetylene as the fuel.

In oxygen cutting operations, the objective is to raise the temperature of the material to be cut to its ignition point in the shortest possible time to initiate the cutting action and then to maintain the material in the area of the cut at this ignition temperature as the cutting action progresses across the material.

To accomplish this objective in the most efficient manner, there is an optimum combination of cutting torch injector and throat that will provide the best operation for a given preheat gas flow and pressure range and a given type of fuel gas; that is, the injector of a low pressure injector-type torch is tailored to supply a limited range of preheat flows with a given type of fuel gas. There is one optimum throat diameter in combination with this injector which will provide the optimum performance.

Should the preheat flow range required for a particular cutting operation be either above or below that for which the throat was designed, the result will be a sacrifice in performance by way of longer initial preheat time, longer cutting time to complete the cut, and a poor quality cut. This is due to the fact that the primary function of the throat section of an injector-type torch is to provide just the right build-up of gas velocity directly downstream of the injector to produce the most efficient aspiration of fuel gas into the mixed gas flow (combined oxygen and fuel gas preheat gas).

If the diameter of the throat section is less than the optimum, the effect is to destroy the injector aspirating efficiency due to a choking off of the injector through a buildup of gas pressure just ahead of the throat section. If the diameter of the throat is greater than the optimum, there will be an insufficient build-up of gas velocity for maximum efficiency of aspiration. Similar results will be had with the use of a fuel gas other than that for which the injector and throat were designed.

In standard cutting torch apparatus, while the injector unit is easily replaced, the throat is an integral part of the torch assembly and not an easily replaced item. That is, it is necessary to disassemble the torch head from the cutting oxygen tube and mixed gas tube, install a new mixed gas tube containing the desired size throat, and then reassemble the head in order to replace the throat section of the torch. As a result, a given standard cutting torch readily provides optimum operation only for one

2

type of fuel gas and then only for a limited range of preheat gas flows. In order to go from one fuel gas to another or to enlarge the preheat flow range of a given fuel gas in order to cut material either thinner or thicker than that for which the torch was originally intended, a different throat section has to be installed in the torch in the time consuming manner outlined above to obtain optimum operation.

Because of this lack of ready adaptability to suit varying cutting requirements on the part of standard cutting torches, it is necessary for the user to either stock a multiplicity of cutting torches, the number depending upon the range of cutting applications prevailing in his particular shop, or suffer a sacrifice in efficiency of operation in terms of longer cutting times and poorer cut quality. Either result is undesirable from an economics point of view. Stocking a multiplicity of torches involves a large initial capital outlay as well as large continuing maintenance costs. If efficiency of operation is sacrificed, poor quality cuts may well result in an increase in subsequent machining required as well as higher labor costs due to the increase in labor time required to complete a given cutting operation.

The cutting torch of this invention supplies the desired degree of versatility in performance by providing a torch which is readily converted to produce the optimum operating performance over a wide range of preheat gas flows and types of fuel gas. This has been accomplished according to the invention by making the throat section of the torch an integral part of an easily replaceable injector-throat assembly. Thus, it is possible to adapt the cutting torch of the invention to provide the optimum operating conditions required for a given application merely by inserting an injector-throat assembly specifically tailored for the particular fuel gas and preheat flow needed. Therefore, instead of stocking a multiplicity of cutting torches, it is merely necessary for the user, having a variety of cutting operations to perform, to stock a sufficient number of injector-throat assemblies to cover his range of operations.

An additional advantage gained from having the throat section of the torch an integral part of the injector-throat assembly is that the end clearance between the forward end of the injector unit and the mouth of the throat section is maintained at a fixed value. This end clearance is a critical factor in maintaining preheat flame stability; that is, resistance to backfire and flashback; and there is an optimum clearance which provides the greatest degree of stability.

50 In the drawings:

FIG. 1 is a plan of a blowpipe embodying the invention; FIGS. 2 and 3 are front and rear portions of a longitudinal cross section through the blowpipe shown in FIG. 1;

55 FIG. 4 is a cross section through the valve block;

FIG. 5 is an enlarged cross section of the central portion of the blowpipe; and

FIG. 6 is a cross section taken along line 6—6 of FIG. 5.

60 The cutting blowpipe shown in the drawings comprises a nozzle head H connected by a cutting oxygen tube C and a preheat gas conduit M to a valve block B to which oxygen is supplied at inlet O and fuel gas at inlet A.

Oxygen enters the valve block B from the inlet O through a passage 10 into chamber 11, from which its passage to the cutting oxygen tube C and the preheat gas conduit M is regulated by valves 12 and 13 respectively.

65 Thus the combustion-supporting oxygen passes from the chamber 11 to a duct 14 in the valve block, the far end of which provides a valve seat and is closed by the valve 13. This valve is carried by a threaded valve stem 15 operated by a handle 16 to move against the valve seat

associated with the duct 14 or to be retracted from this seat into a valve chamber 17 which is formed in the valve block B.

The valve block B has a through bore 19 aligned with preheat gas conduit M, and a cross passage 18 connects the valve chamber 17 with the back end of the bore 19. Accordingly, by turning the handle 16, combustion-supporting oxygen may be permitted to flow into the valve chamber 17 and thence through the cross passage 18 to the back end of the bore 19.

The flow of fuel gas from inlet A to the forward end of bore 19 in the valve block B, through passages not shown, is regulated by valve 50, similar in construction to valve 13.

According to the present invention, the preheat gas conduit M is a continuous tube from the valve block B, to which it is gas-tightly connected as by silver soldering at 21, to the nozzle head H to which it is gas-tightly connected as by silver soldering at 22. The injector throat assembly inserted through the bore 19 in the valve block B and preheat gas conduit M comprises a throat section 20, an injector 23, a preheat oxygen tube 24, and an injector sealing member 25, all rigidly connected together.

The throat section 20 has a central passage 28 with a front portion 29 expanding forwardly in conical form toward the head H, and a back portion 30 expanding rearwardly in conical form and terminating in a cylindrical entrance 32 having an annular rim 33.

The injector 23 has a conical nose 34 entering the conical rear passage portion 30 of the throat section with a fixed optimum clearance, and a cylindrical portion 35 extending rearwardly and having radial fins 36 fitting inside the cylindrical entrance 32 of the throat section. The injector also has an annular groove 37 intersecting the fins 36. The sections 39 of the fins 36 to the rear of annular groove 37 are laterally extended to contact the cylindrical wall of the preheat gas tube M. The forward faces of these fin extensions adjacent the groove 37 are fused to the rear annular rim 33 of the throat section as by silver solder 38. The arcuate passages 51 between the fins 36 provide communication for fuel gas flow from the annular passage 54, between the oxygen tube 24 and the preheat gas conduit M, to the fixed optimum clearance between the conical nose 34 of the injector and the conical rear passage portion 30 of the throat section.

The injector 23 also has a central passage 40 aligned with the throat passage and terminating in a rear socket 42. The front end of the oxygen tube 24 is fitted into this socket and silver soldered into the sealing member 25 in registry with axial passage 53 in the sealing member 25. O ring 52 is an annular groove in the periphery of sealing member 25 seals off the oxygen inlet into the rear of bore 19 from the fuel gas inlet in the forward end of bore 19.

Thus, preheat oxygen entering the rear of bore 19 passes 55 successively through axial passage 53 in sealing member 25, oxygen tube 24, central passage 40 in the injector 23 to the central passage 28 in the throat section 20. Fuel

gas entering the forward end of bore 19 flows through annular passage 54 to arcuate passages 51 and thence to the clearance between conical nose 34 and conical rear passage portion 30 where it is aspirated into the central passage 28 in the throat section 20 to become mixed with the preheat oxygen.

This injector throat assembly of throat section 20, injector 23, tube 24 and sealing member 25 is inserted through the bore 19 with the front end of the throat section 20 abutting the inside of the nozzle head H. The nut 45 is tightened to compress spring 46 to hold the assembly in position under spring pressure and still allow for heat expansion of the parts.

It will be seen that by having the throat section 20, 15 injector 23, preheat oxygen tube 24 and sealing member 25 all rigidly connected together not only provides for their ready removability from the cutting torch as an integral assembly but also ensures maintaining a fixed optimum clearance between the conical nose 34 on the injector 23 and the conical rear passage portion 30 of the throat section 20 necessary to maintain preheat flame stability.

What is claimed is:

In a cutting blowpipe having a valve block and a nozzle head, a preheat tube connecting said valve block to said nozzle head, and a removable injector-throat assembly inserted through said valve block into said preheat gas tube; said unit comprising a throat section 25 separate from said preheat gas tube and of a diameter to slide inside thereof forwardly toward said nozzle head; said throat section having an axial passage expanding rearwardly in conical form and terminating in a cylindrical entrance having an annular rim; an injector having a conical nose entering said conical form with a clearance 30 and a cylindrical portion extending rearwardly therefrom inside of said cylindrical entrance, and a rear portion of larger diameter fitting inside said preheat tube, said injector also having an axial passage aligned with said throat passage, said injector also having longitudinally 35 extending fuel gas passages outside of and surrounding said axial passage, said rear portion of said injector having a forward face outside of said surrounding passages and rigidly and permanently secured to said annular rim of said throat section, whereby removal of said injector 40 out through said valve block carries said throat section therewith.
